UNITED STATES PATENT OFFICE

135,930

DESIGN FOR A GAME BOARD

Ralph C. Cobb, Los Angeles, Calif.

Application February 11, 1943, Serial No. 109,526

Term of patent 14 years

To all whom it may concern:

Be it known that I, Ralph C. Cobb, a citizen of the United States, residing at Los Angeles, in the county of Los Angeles and State of California, have invented a new, original, and ornamental Design for a Game Board, of which the following is a specification, reference being had to the accompanying drawing, forming part thereof.

I claim:

The ornamental design for a game board, as shown.

RALPH C. COBB.
